UNITED STATES PATENT OFFICE.

JOHN F. STANDISH, OF WINTHROP, MASSACHUSETTS, ASSIGNOR TO UNITED SHOE MACHINERY CORPORATION, OF PATERSON, NEW JERSEY, A CORPORATION OF NEW JERSEY.

FINISHING MACHINE.

Application filed November 10, 1922. Serial No. 600,169.

To all whom it may concern:

Be it known that I, JOHN F. STANDISH, a citizen of the United States, residing in Winthrop, in the county of Suffolk and 5 State of Massachusetts, have invented certain Improvements in Finishing Machines, of which the following description, in connection with the accompanying drawings, is a specification, like reference characters on 10 the drawings indicating like parts in the several figures.

This invention relates to machines for finishing leather and is herein disclosed as embodied in a machine for waxing and burnishing the edges of heels of boots and shoes. In Letters Patent of the United States No. 1,494,388, granted May 20, 1924, upon my copending application Ser. No. 440,658, filed 15 Jan. 28, 1921, there is disclosed a heel finishing machine having a tool comprising a series of rotary disks which oscillate during 20 their rotation. These disks have their centers of rotation laterally displaceable so that the tool as a whole can be made to conform 25 to any desired heel contour. One object of the present invention is to provide an improved burnishing machine of this general type although in some aspects, the invention obviously has a broader field of application. 30 One feature of the invention relates to mechanism for rendering a finishing tool self heating. In accordance with this feature as herein illustrated, rotary burnishing elements are mounted with their side faces 35 in rubbing contact and, preferably, their centers of rotation are displaced laterally so that during the actuation of the tool the side faces of the elements rub against each other and thus create heat by friction.

Another feature relates to improved mechanism for supplying a tool with a finishing medium such as molten wax. In the illustrated machine, a wax pot fixed outside the tool supplies melted wax in a regulated 45 degree to a conduit which conducts the wax to the interior of the tool made up of a series of disks whence the wax spreads outwardly to lubricate the bearings of the rubbing disks and to supply their peripheries 50 with the finishing medium.

The invention provides also, as a further feature, novel auxiliary mechanism for supplying a finishing medium such as molten wax. In connection with an organization

comprising an applying member movable 55 from a point where it receives a supply of wax to a point in contact with the tool and a transfer member which dips in a wax receptacle and removes a small quantity of wax for presentation to the applying member, novel mechanism is provided such that the force applied to the movable transfer member is rendered ineffective when the wax in the receptacle is congealed and another 60 novel mechanism is provided which is constructed and arranged to hold the applying member either in active or inactive relation to its operating mechanism.

Still another feature relates to mechanism for reducing vibration resulting from rapid 70 oscillation of the burnishing tool. In accordance with this feature, the machine shown has a balancing member in the form of a weight rockably mounted on the same axis as that upon which the tool oscillates, 75 and mechanism is provided to rock the tool and the balancing member simultaneously in opposite directions.

In accordance with another feature of the invention, means are provided in an arrangement in which there is a tread rest adjacent to the operating tool, for moving the elements of the burnishing tool, which are at one side of the tread rest, to an inoperative 80 position, thus rendering it unnecessary to supply wax to the inoperative sections of the tool and avoiding the possibility of injury to the work by contact with a portion of the tool beyond the work-engaging portion.

These and other features and advantages 90 of the invention will appear from a consideration of the following specification and accompanying drawings in which,

Fig. 1 is a front elevation with some parts 95 in section;

Fig. 2 is a perspective view of the heating means;

Fig. 3 is a left-hand side elevation;

Fig. 4 is a perspective view of auxiliary 100 wax supplying mechanism;

Fig. 5 is a horizontal section of the burnishing tool;

Fig. 6 is a vertical section of the tool showing one of the rubbing elements in side 105 elevation.

The numeral 10 designates a series of rotary burnishing elements in the form of

rings, the side faces of which are in sliding contact. The rings are rotatably mounted on ball bearings 12 in raceways carried by bearing members 14 which are hollow and have upper and lower flat faces 16 to slide on corresponding flat faces of adjustable carriers 18. There is a space 20 between each bearing member and its corresponding carrier to allow limited sliding movement as when a piece of work is pressed against the peripheries of the burnishing elements. A spring 22, interposed between each bearing member and its carrier, imparts to the burnishing tool a yielding quality so that it can search out and find the inequalities in the surface of the work. There is a rectangular slot in each carrier 18 to slidably engage flat faces 24 on a support 26 in the form of a bar which is curved horizontally, preferably in accordance with the contour of an average heel. There is a space 28 between each carrier and the front of the support 26 to allow independent adjustment of the carriers laterally and springs 30, which are of less strength than the spring 22, are interposed between these members and tend to move each carrier forwardly to normal position. The series of adjustable carriers 18, after lateral adjustment, (effected by pressing a heel rearwardly against the disks 10) can be clamped between a flanged collar 32 and a collar 34. The collar 32 is loose but not rotatable on the support 26 and the other collar 34 is fixed to the support. The springs 22, being stronger than the springs 30, will not yield until the carriers have been clamped in adjusted position. The support 26 at one end passes through a slot in a rocking bearing bracket 36, there being a nut 38 threaded on the end of the support to clamp the carriers between the collars 32 and 34.

The burnishing disks are rotated by the following mechanism: A disk 40 has its hub rotatably supported on an extension 42 of the support 26 and near its periphery has a member 44 pivotally connected to jointed sections 46 and 48 which constitute a drive pin extending horizontally through rectangular slots 50 in the burnishing disks 10. These jointed sections allow the disks to be driven without cramping as they oscillate with the support 26 and rotate about centers that are laterally displaced. The disk 40 is connected by a universal joint 60 to a short shaft 62 in turn connected through a universal joint 64 to a drive shaft 66. The universal drive is necessitated by the fact that the tool oscillates as well as rotates. The tool is easily removable as a unit on account of the provision of a detachable cap plate 70 which retains the end of the support 26 to the bearing bracket 36. Upon removal of the cap plate, the left end of the support 26 can be swung forwardly and its

right end extension 42 slipped out from the hub of the disk 40. The jointed drive pin swings so that it does not interfere with this action.

The tool is provided with auxiliary heating means which may be used if desired when the tool is first started, or when the wax is congealed. The bracket 36 has two rearwardly extending arms (see Fig. 3) in which are clamped upper and lower hollow rods 72 and 74 on which are fixed two heating plates 76 and 78 in the form of U-shaped castings (Fig. 2) which lie along the opposite side of the tool and embrace the support. These plates being open at the front do not interfere with removal of the tool. They are connected and braced at their forward ends by detachable rods 80 and 82. Each plate carries an upper heating unit 84 (Fig. 3) and a lower heating unit 86, one heating plate lying at the side of the outside burnishing disk 10 and the other lying at one side of the disk 40 thereby conducting the heat to the peripheries of the rubbing disks. Lead wires 87 extend from the heating units to a connection block 88 hung from the rods 72 and 74 and spiral spring leads 89, under compression, connect the block 88 with a block 90 fixed on the frame and connected with a source of current.

To avoid tool marks on the work, the tool is oscillated during rotation about an upright axis passing through the central portion of the tool. An extension 91 (Figs. 1 and 3) of the rocking bearing bracket 36 is bent into alignment with the center of the tool and clamped to a vertical shaft 92, the upper end of which has a tapered bearing in a frame arm 94. The lower end of the shaft 92 is received in a cupped bearing 96 adjustably threaded in a lower frame arm 98. A rearward arm 100 joined to the extension 91 is connected by a link 102 (Fig. 1) with an eccentric 104 on a substantially vertical shaft 106 driven by spiral gears 108 from the main drive shaft. A balancing member in the form of a weight 110 is rockably mounted on the shaft 92 and has an arm 112 connected by a link 114 with an eccentric 116 on the shaft 108. The tool and the weight are rocked simultaneously in opposite directions, this being effected by placing the high points of the eccentrics 180° apart, or in an opposite phase. The eccentrics and shaft are confined within a casing 118 extending downwardly from the frame. Thus the burnishing rings or disks 10 are oscillated slightly from side to side, as they are rotated, and tool marks are avoided.

The finishing medium or wax is supplied from a receptacle 122 (Figs. 3 and 4) carried above the tool on a bracket 120 which is vertically adjustable on the frame. A heating unit 124 is inserted in a boss at the

forward under side of the receptacle to keep the wax in a melted condition, and a valve 126 directs a regulated supply of wax to a conduit 128 which is bent around in close proximity to the heating unit 84 and thence to an opening 130 (Fig. 5) in the collar 32 whence a duct 132 (Figs. 5 and 6) through the support 26 carries the wax to the interior of the tool. From this point 10 the actuation of the tool causes the wax to spread outwardly not only lubricating the ball bearings 12 and the contacting surfaces of the end disk 10 with the flange of the collar 32 but also supplying the periphery 15 of the tool with the necessary finishing medium.

Two screws 134 (Fig. 3) are threaded into the upper arms of the heating plates and carry a spring pressed bar 136 having a pad 20 or scraper 138 (Fig. 1) lying against the periphery of the tool to distribute the wax evenly over the surface. An auxiliary wax applying mechanism (Figs. 3 and 4) is provided comprising a pad 140 carried by an 25 arm hung on the pivot rod 142 at the front of an arm 144 constructed as an open frame which is large enough to embrace the sides of the receptacle. The arm or frame 144 is pivotally connected by a rod 146 to the 30 ends of arms 150 and 152 fixed to a rock shaft 154 journaled in a fixed bearing 156 on the frame. The wax applying member is oscillated from a position in contact with 35 the periphery of the tool to a position above the wax receptacle by a slotted arm 158 (Fig. 3) fixed to the rock shaft 154 and receiving a slide block 160 connected by a pin to a pulley 162 rotatably mounted on the bracket 120. The pulley is driven by 40 a belt 164 from a second pulley 166 fixed to a shaft 168 driven by gears 170 (Fig. 1) from a second shaft 172, in turn driven by a spiral gear 174 meshing with a gear 176 (Fig. 3) on the shaft 106. The path of 45 movement of the wax applying member is controlled by a projection 182 (Fig. 4) from the arm 144 which rides on a cam surface 184 fixed to the wax receptacle. The pad 140 is retained at the proper angle by rod 50 186 pivotally connected to the arm 150 and to an extension on the pad carrying arm.

At times, both means for applying wax will be used. At other times, the auxiliary mechanism will not be needed. Accordingly, the pad is yieldingly held in one of two positions, either against the periphery of the tool or in a raised position, by a spring 192 (Figs. 1 and 3) interposed between a pin 190 on the arm 144 and a pin 55 194 on a lever 196 which is hung on the rod 146. The effect of this spring 192 is varied, at the will of the operator, by swinging the lever 196, movement of which in one direction is limited by a short arm 198 which contacts with a pin 200 on the arm 60

152. When the lever 196 is in the position shown in Fig. 3, the pad 140 is depressed by the spring and the auxiliary mechanism is effective. If the operator rocks the lever 196 about the rod 146 until its long arm 70 contacts with the pin 200, the line of the spring will lie above the rod 146 and hence retain the arm 144 in a raised position with the pin 190 resting against an extension 202 of the arm 152, thus rendering the 75 auxiliary mechanism ineffective.

As the pad 140 is swung above the forward portion of the wax receptacle, wax is transferred from the receptacle to the pad by a transfferer 206 carried on arms 208 80 pivotally mounted at 210 at the rear of the receptacle. The transfferer is actuated by the movement of the applying member, there being a bell crank lever 212 pivoted on the transfferer arm 208 and lying in the path 85 of the rod 146. As the rod 146 approaches its rearward limit of travel, it contacts with the bell crank lever 212 and lifts the transfferer from the wax into contact with the under side of the pad 140. To prevent actuation of the transfferer when the wax is cold, a rearwardly extending arm 214 on the bell crank lever 212 has interposed between it and an extension 218 of the arm 208, a spring 216. This spring will give, if any 90 abnormal resistance to the movement of the transfferer is encountered.

A curved tread rest 222 (Figs. 1 and 3) for the heel of a shoe is mounted adjacent to the periphery of the tool on a rod 223 100 which has sliding adjustment parallel to the tool axis. A lever 224 having a cam face 226 is pivoted to the rest and is designed to aid the operator in pressing some of the rubbing disks 10 rearwardly against 105 the tension of the springs 30 and 22 when the disk carriers 18 are set free by loosening the clamping nut 38. The operator is thus enabled to select just enough disks to cover the work being treaded and the others, or 110 those to the right of the tread rest, are movable to inoperative position where they are held by their carriers on again turning up the clamp nut 38.

The operation of the machine is believed 115 to be apparent from the above description. Although the invention has been shown and described by reference to a specific machine, it should be understood that it is not necessarily restricted to the illustrated construction.

Having fully described my invention, what I claim as new and desire to secure by Letters Patent of the United States is:

1. In a machine of the class described, a 125 self heating burnishing tool comprising a series of burnishing elements arranged to rub against each other, and means for actuating said elements to heat the tool and burnish the work. 130

2. In a machine of the class described, a self heating burnishing tool comprising a series of contacting burnishing elements, and means for rotating the elements to heat the tool and burnish the work.
3. In a machine of the class described, a self heating tool comprising a series of burnishing elements, each mounted to rotate about a center and contacting with an adjacent burnishing element, and means for causing adjacent burnishing elements to rub against each other.
4. In a machine of the class described, a self heating tool comprising a series of contacting burnishing elements each mounted to rotate about a center, means for fixing the centers of rotation of the elements in different lateral positions, and means for rotating said elements to cause them to rub against each other and to burnish the work.
5. In a machine of the class described, a self heating tool comprising a series of rings lying in sliding contact, circular bearings rotatably supporting the rings and having their centers out of alignment, and means for rotating the rings to heat the tool and rub the work.
6. In a machine of the class described, a support, a non-rotatable flanged retaining collar on said support, a burnishing tool rotatably mounted on the support adjacent to said flange, a receptacle for molten wax fixed outside the tool, and means for conducting wax through the interior of the tool to the burnishing surface and to the bearing surface between said flanged collar and said tool.
7. In a machine of the class described, a tool comprising a series of rotary burnishing elements, a receptacle for molten wax outside the tool, and means for conducting wax to the periphery of the tool through the interior thereof.
8. In a machine of the class described, a tool comprising a series of burnishing elements, bearings for rotatably supporting said elements, and means for introducing melted wax to the interior of the tool to lubricate the bearings and supply finishing material to the burnishing surface.
9. In a machine of the class described, a support, bearings for a series of burnishing elements, carriers interposed between the bearings and the support with capacity for adjustment relatively to either, springs interposed between the bearings and the carriers, and weaker springs interposed between the carriers and the support.
10. In a machine of the class described, a rotary burnishing tool, a support for the tool, means for rocking the support about an axis, and means rockable simultaneously with the support in an opposite sense to reduce vibration.
11. In a machine of the class described, a rotary burnishing tool, a pivotal mounting for said rotary tool, a balancing member rockable on said pivot, and means for simultaneously rocking said tool and balancing member in opposite directions.
12. In a machine of the class described, a burnishing tool, a support for the tool having a pivotal mounting, a balancing member rockable on said pivot, and oppositely moving links connected to the support and the balancing member to rock them in opposite directions.
13. In a machine of the class described, a support, a series of burnishing elements rotatably mounted on the support with their axes out of alignment, a jointed drive pin extending through said burnishing elements, and means for driving the pin to rotate the burnishing elements.
14. In a machine of the class described, a support, a series of burnishing elements rotatably mounted on the support with their axes out of alignment, a disk rotatable on said support, a pin pivotally connected to said disk and extending through said burnishing elements, and means for driving the disk to rotate the elements.
15. In a machine of the class described, an oscillating support, a series of burnishing elements rotatably mounted on the support, a disk rotatable on the support, a jointed pin connected to said disk and extending through said burnishing elements, a drive shaft, and universal connections between said drive shaft and said disk.
16. In a machine of the class described, a receptacle for a finishing medium, a finishing tool, an applying member movable from a point near the receptacle to the finishing tool, a transfer member movable by the applying member from within the receptacle into contact with the applying member, and means for rendering ineffective the force applied by the applying member to move the transfer member when the finishing medium is congealed.
17. In a machine of the class described, a receptacle for a finishing medium, a finishing tool, an applying member movable from a point near the receptacle to the finishing tool, a transfer member movable by the applying member from within the receptacle into contact with the applying member, and a yielding abutment interposed between the transfer member and the applying member.
18. In a machine of the class described, a finishing tool, an arm, an applying member pivoted to the arm, a spring for holding the applying member against the finishing tool, and means for moving one end of the spring to cause the spring to hold the applying member in another position.
19. In a machine of the class described, a finishing tool, an arm, an applying member pivoted to the arm, a lever pivoted to the

- arm, a spring interposed between the applying member and the lever, and means for holding the lever in a plurality of positions to cause the spring to hold the applying member in operative or inoperative position.
20. In a machine of the class described, a burnishing tool having a plurality of individual rubbing elements, a tread rest adjacent to the tool, and means for moving the rubbing elements at one side of the tread rest to an inoperative position.
21. In a machine of the class described, a burnishing tool having a plurality of individual rubbing elements, a tread rest adjacent to the tool, a cam adapted to be brought into operative relation to the elements of the tool to move the same, and means for moving the cam to move some of the rubbing elements out of operative position.
22. In a machine of the class described, a burnishing tool having a plurality of individual rubbing elements, a tread rest adjacent to the tool, a cam carried by the tread rest, and means for moving the cam to move some of the rubbing elements out of operative position.
23. In a machine of the class described, a burnishing tool having a plurality of individual rubbing elements, a tread rest adjacent to the periphery of the tool, means for adjusting the tread rest along the tool to select the desired number of rubbing elements for use, and means for moving the remaining rubbing elements to an inoperative position.
24. In a machine of the class described, a burnishing tool having a plurality of individual rubbing elements, a tread rest adjacent to the periphery of the tool, means for adjusting the tread rest along the tool to select the desired number of rubbing elements for use, a cam constructed and arranged to engage the remaining rubbing elements, and means for actuating the cam to move said remaining rubbing elements out of operative position.
25. In a machine of the class described, a support, a burnishing tool carried by the support, and a heating plate at the side of the tool, said plate being open at the front to allow removal of the tool with its support.
26. In a machine of the class described, a support, a burnishing tool carried by the support and comprising a series of rotary rubbing elements, and a heating plate at each side of the tool, said plates being open at the front to allow removal of the tool with its support.
27. In a machine of the class described, a support, a burnishing tool carried by the support, a rocking member, a U-shaped heating plate carried by the rocking member, and a detachable connection between the rocking member and the support.
28. In a machine of the class described, a bracket, a burnishing tool mounted for rotation on said bracket, and heating plates fixed to said bracket at the sides of the rotary tool.
29. In a machine of the class described, a bracket, a burnishing tool rotatably and removably mounted on said bracket, and a U-shaped heating plate fixed to said bracket at the side of the rotary tool.
30. In a machine of the class described, a rocking member, a support extending from the rocking member, a rotary burnishing tool carried by the support, rods carried by said rocking member and extending across the periphery of the tool, and heating plates secured to the rods.
31. In a machine of the class described, a bracket having a pair of arms, a rotary burnishing tool carried by the bracket, rods extending across the periphery of the tool from said arms, and heating means supported by said rods at the sides of the tool.
32. In a machine of the class described, a rocking member, a burnishing tool carried by the rocking member, heating plates carried by the rocking member and lying along the sides of the tool, and a connection between said plates.
- In testimony whereof I have signed my name to this specification.

JOHN F. STANDISH.
